UNITED STATES PATENT OFFICE

106,353

DESIGN FOR AN ENSEMBLE DRESS

Sally Messina, New York, N. Y.

Application August 3, 1937, Serial No. 70,818

Term of patent 3½ years

To all whom it may concern:

Be it known that I, Sally Messina, a citizen of the United States, residing in the city and State of New York, have invented a new, original, and ornamental Design for an Ensemble Dress, of which the following is a specification, reference being had to the accompanying drawing constituting a part thereof.

I claim:

The ornamental design for an ensemble dress substantially as shown.

SALLY MESSINA.
